POLIO EXERCISING MACHINE

Marion A. Park, St. Louis, Mo.

Application September 8, 1947, Serial No. 772,753

6 Claims. (Cl. 272—79)

1

My present invention relates generally to surgical appliances of the self-exercising type and more specifically to an improved polio exercising machine, that is operated by the patient for exercising the legs, arms, and shoulders, and to this end the machine includes a horizontally reciprocable exerciser for the legs and a vertically reciprocable exerciser for the arms and shoulders, together with resiliently operating means for actuating the return stroke or movement of each of the exercisers.

The exercising apparatus includes a minimum number of parts that may with facility be manufactured at low cost of production, and the parts may be assembled with convenience, to constitute a reliable and durable structure that is simple in construction and which may with ease be operated by the patient while sitting in a chair.

The invention consists in certain novel features of construction and combinations and arrangements of parts involving the above mentioned elements as will hereinafter be described and more particularly set forth in the appended claims.

In the accompanying drawings I have illustrated a complete example of a physical embodiment of the invention wherein the parts are combined and arranged in accord with one mode I have devised for the practical application of the principles of my invention. It will however, be understood that changes and alterations are contemplated and may be made in these exemplifying drawings and mechanical structures, within the scope of my claims, without departing from the principles of the invention.

Figure 1 is a view in side elevation of an exercising appliance in which my invention is physically embodied.

Figure 2 is a perspective view of the frame portion of the appliance with some operating parts supported thereon.

Figure 3 is a perspective view of the foot-pressed reciprocable wheeled truck for actuating the mechanism; and

Figure 4 is a transverse vertical sectional view at line 4—4 of Fig. 1.

In carrying out my invention I utilize an upholstered chair having a conventional seat and back as 1 and 2 and having a tubular supporting frame including arms 3, and legs forming a U-shaped floor bar or base 4 upon which the chair is firmly supported. A supporting frame for the exercising appliance includes a rear tubular upright post 5 rigid with the chair frame, an overhead horizontal bar 6 and a front post 7 that is united at its lower end with a cross bar 8 that is provided with end legs 9.

The cross bar 8 is united, as by welding with a rail-frame that includes laterally spaced horizontal rails 10, 10 of tubular construction, and a cross brace 11 unites the rails near their inner

ends that are affixed to the chair frame. The chair frame, the overhead frame, and the rail frame, are all rigidly united, as by welding, or in other suitable manner, to provide a strong and substantial structure for the operating parts of the appliance.

Spaced in front of the chair and mounted upon the horizontal rails 10, 10, a leg-exercising truck is reciprocably mounted and adapted to be pressed by the feet or pushed by the patient who occupies 10 the chair, for an outstroke or movement of the truck, and for rendering operative the horizontally movable exerciser and the vertically movable exerciser. For this purpose the truck is 15 equipped with a horizontal floor or leg-rest 12, and an upright slightly inclined foot-rest or presser-board 13, and four wheels as 14 are journaled on two spaced axles 15, the wheels being provided with exterior annular grooves 20 complementary to the tubular track rails or tubes 10, 10, and each wheel is equipped with a guard 25 as 16 welded to an axle and provided with a retaining arm 17 to prevent derailment of the truck.

For actuating the operating parts the truck is 25 provided with a depending arm or leg 18 to which an operating cable 19 is attached, and the cable passes to the rear over a guide pulley 20 that is journaled in a bracket 21 mounted at the under side of the chair seat. From pulley 20 the cable 30 extends forwardly and its forward end is attached to a helical tension spring 22 that is anchored by means of an adjusting screw bar 23 to a post or lug 24 depending from the cross bar 8. By means of a wing nut 25 bearing against the anchoring lug the screw bar may be adjusted in 35 its threaded bearing to decrease and to increase the tension of the spring and thereby accommodate the movement of the exercising truck to the variable strength of the patients.

The foot-pressed and resiliently returned truck 40 is also operatively connected with the vertically reciprocable exerciser for the arms and shoulders that is suspended in the overhead frame where it is readily accessible by hand-grasp to the patient occupying the chair. For this purpose a second cable 26, is attached to the front end of the truck and extended forwardly to, under, and around a guide pulley 27 journaled in a bracket 28 fixed to the lower end of the front post 7. The cable then 45 extends upwardly and around an elevated guide pulley 29, journaled in a corner of the overhead frame, and thence rearwardly along the horizontal bar toward an adjustable suspending head 30 that is slidably mounted on the bar and fixed 50 in adjusted position as by a set screw 31.

This adjustable anchoring head for the cable, and from which the adjustable arm and shoulder exerciser is suspended, is equipped with a pair of 55 depending arms 32 in which an oscillating pulley 33 is journaled at 34, and the end of the cable 26

is anchored at 35 to the pulley for imparting thereto one of its oscillating strokes.

A tangentially arranged lever-arm 36 is attached to the fulcrum-pulley 33 and the arm is provided with a series of spaced holes as 37 for attachment of a sling having a suspending hook 38 and a handle bar or cross bar 39, and the exercising sling may be suspended from a selected hole of the lever arm to vary the leverage of the arm.

In actual practice the patient sits in the chair with his knees bent upwardly, his legs resting upon the truck, and with his feet against the presser board 13 of the truck; then by pulling down the knees and straightening the legs, the truck is pushed away from the chair for an out-stroke against the tension of the spring 22 and the spring is extended. When foot-pressure against the board is released the contracting spring pulls the truck on an in-stroke toward the chair, and this reciprocating movement of the truck is repeated as required, for exercising the legs.

The arm and shoulder exerciser may also be utilized simultaneously with the leg exerciser, and the patient may grasp the hand bar 39 with both hands at the first downward movement of the sling, which is permitted with the out-stroke of the truck. Thus the sling and the cross bar of the arm and shoulder exerciser are vertically reciprocated by the horizontal out-stroke and in-stroke of the truck, and the arms and shoulders of the patient are exercised as needed.

The exercising appliance may be adjusted within a wide range for adults and children by varying the tension of the spring 22; and also by adjusting the position of the suspending head 30 on the overhead bar, as well as by adjusting the location of the hanger or sling on the lever arm 36.

The appliance may selectively be used for simultaneously exercising both of the upper and lower limbs; for exercising the lower limbs; and also for exercising the upper limbs.

Having thus fully described my invention, what I claim as new and desire to secure by Letters Patent is:

1. In an exercising appliance including a chair for a patient and a rigid rail frame, the combination with a wheeled foot-pressed truck reciprocably mounted on the rail frame, of a return cable attached at one end to the truck and anchored at its other end to the frame, an intermediate guide pulley mounted on the chair for the cable, and a retracting spring connected with the cable for an in-stroke of the truck.

2. In an exercising appliance including a chair for a patient, a rigid rail frame, and an overhead frame, the combination with a wheeled foot-pressed truck reciprocably mounted on the rail frame, and resilient means for returning the truck toward the chair, of a vertically reciprocable hand-exerciser mounted in the overhead frame for arms and shoulders, and operative connections from the reciprocating truck for actuating the overhead exerciser.

3. In an exercising appliance including a chair, a rigid rail frame and a rigid overhead frame, the combination with a wheeled foot-pressed truck reciprocably mounted on the rail frame, and a hand-grasped exerciser mounted for vertical reciprocation in the overhead frame, of resilient means coacting with the chair and rail-frame for a return movement of the truck, and operative connections from the reciprocating truck for actuating the hand-grasped exerciser.

4. In an exercising appliance including a chair, a guide pulley mounted on the chair, a rigid rail frame and a rigid overhead frame, the combination with a wheeled foot-pressed truck reciprocably mounted on the rail frame, and a hand-grasped exerciser mounted for vertical reciprocation on the overhead frame, of a cable attached at one end to the truck and passing around the guide pulley mounted on the chair, an adjustable screw bar mounted in the rail frame, and an extensible spring anchoring the other end of the cable to said screw bar.

5. In an exercising appliance including a chair, a rigid rail frame and an overhead frame, the combination with wheeled foot-pressed truck reciprocably mounted on the rail frame and resilient means for returning the truck toward the chair, of an adjustable head mounted on the overhead frame, a pulley having a rigid lever arm and journaled in said head, a hand-grasped sling pivotally mounted on the lever arm, an operating cable having its end connected respectively to said truck and pulley, and guide pulleys for said cable.

6. In an exercising appliance including a chair, a rail frame and an overhead frame, the combination with a foot-pressed truck reciprocably mounted on the rail frame, and a hand-grasped exerciser mounted for vertical reciprocation in the overhead frame, of resilient means causing a return movement of the truck, and operating cable connections from the truck for actuating the hand-grasped exerciser.
